NEVIUS, OF FLEMINGTON, NEW JERSEY.

COMBINED FRUIT-BASKET AND COVER.

SPECIFICATION forming part of Letters Patent No. 284,064, dated August 28, 1883.

Application filed January 27, 1883. (No model.)

To all whom it may concern:

Be it known that we, JOHN W. ROCKAFELLOW, of Stockton, in the county of Hunterdon and State of New Jersey, and PETER T. B. NEVIUS, of Flemington, in the county of Hunterdon and State of New Jersey, have invented a new and Improved Combined Fruit-Basket and Cover, of which the following is a full, clear, and exact description.

10 The object of our invention is to provide a new and improved fruit-basket in which the cover is made integral with the basket.

The invention consists in a basket made of splints projecting above the top ring thereof, and adapted to be folded over the top of the basket and to form the cover, and in certain combinations and arrangements of parts, substantially as hereinafter more fully set forth and claimed.

20 Reference is to be had to the accompanying drawings, forming part of this specification, in which similar letters of reference indicate corresponding parts in both the figures.

Figure 1 is a perspective view of our improved fruit-basket, showing it open. Fig. 2 is a perspective view of the same, showing it closed.

The basket is made of splints or staves A, usually used in the manufacture of fruit-baskets, which splints are attached at their lower ends to the bottom B of the basket, or are bent to form the bottom. The top ring, C, of the basket is placed against the inner surfaces of the splints, which project a little more

30 than half the upper diameter of the basket above the top ring, C, of the same, and each splint is fastened to the ring C by means of a nail, a. A ring, D, is preferably passed around the bottom of the basket and fastened to the same by means of nails d, driven through the said ring D and the lower ends of the splints into the edge of the bottom B.

40 One splint, A', is made longer than the rest, the distance from the ring C to the end of the splint being a little greater than the upper diameter of the basket. A staple, E, made of sheet metal, or a cross-piece made of a splint, is attached to the outer side of the ring C,

diametrically opposite to the splint A'. If the basket is filled and it is to be closed, the 50 projecting upper ends of the splints are bent over the top of the basket, as shown in Fig. 2, so that the free ends of the splints will be over the middle of the basket. The long splint A' is then bent over the other splints, 55 and its free end is bent down against the outer surface of the ring C and under the staple E. A pin or nail is then passed through an aperture in the staple and an aperture in the long splint A' for the purpose of holding the same 60 in place and to hold the basket closed. If desired, an outer ring can be passed and secured around the upper end of the basket. A wire, G, is passed through and around the splints at about the middle of the height of 65 the basket for the purpose of bracing, stiffening, and strengthening the same. When the basket is stored, the upper ends of the splints are bent upward, and one basket is placed in the other, so as to occupy very lit- 70 tle space.

The above-described basket is much cheaper than the baskets provided with separate covers, and it has the advantage that the cover cannot be lost or mislaid.

75 The baskets can be made in different sizes, for large or small fruit—for instance, peaches, cherries, strawberries, &c.

If desired, two splints A' may be made longer than the rest, which splints are so arranged 80 that when the basket is closed they cross each other.

Having thus described our invention, what we claim as new, and desire to secure by Letters Patent, is—

85 1. A basket made substantially as herein shown and described, with the splints projecting above the top ring of the basket and adapted to be folded over the top of the basket to form a cover, as set forth.

90 2. A basket made with the splints projecting a little more than half the upper diameter of the basket above the top ring of the basket, substantially as herein shown and described, and for the purpose set forth.

95 3. A basket made with the splints project-

ing above the top of the basket, one or two splints being longer than the rest, and of sufficient length to extend across the top of the basket, substantially as herein shown and described, and for the purpose set forth.

4. In a basket, the combination, with the top ring, C, of the splints A, projecting above it, the longer splint A', and the staple E, sub-

stantially as herein shown and described, and for the purpose set forth.

JOHN WESLEY ROCKAFELLOW.
PETER T. B. NEVIUS.
